LINE TAP STICK WRENCH

Stephen P. Becker, Poughkeepsie, N. Y.

Application October 7, 1936, Serial No. 104,407

1 Claim. (Cl. 81—53)

This invention relates primarily to a stick or pole wrench of the socket type, and more particularly to a tool or device for securing tap clamps to primary line wire conductors for the purpose of effecting either permanent or temporary taps to lead conductors.

For this purpose it is desirable that the lineman be able to reach a feed-wire located upon the outer end of a cross-arm, from the pole without being obliged to climb out to the feed-wire in order to install and tighten the clamp on the wire.

Most of the clamps now in use for this purpose are provided with a tightening screw having an eye-head or a flattened circular head that may be engaged either by a hook or socket mounted on the end of a stick by which the lineman can readily reach the feed-wire both to install or remove the clamp from a distance of several feet.

Hooks and other devices on the end of a stick have many disadvantages and a socket wrench is hard to keep in place and to work with.

The object of this invention is to provide a device or tool adapted to be mounted upon the end of a stick, to be employed in locating, attaching, and removing line-tap clamps from feed-wires and the like.

Another object of the invention is to provide a tool which may be temporarily attached to the clamp and by which the clamp may be located on the feed-wire.

Another object of the invention is to provide a tool of this class which shall not require any adjustment and which by rotary movement of the stick may be attached or detached from the clamp bolt.

A further object of the invention is to provide a tool for this purpose that shall be self-contained and composed of few parts combining strength and durability.

With these and other objects in view, my invention consists in certain novel construction and combination of parts that will hereinafter be fully described and claimed and further illustrated by the accompanying drawing which forms a part hereof, and in which like figures of reference refer to corresponding parts in all of the views, and it is understood that slight changes may be made without departing from the spirit of the invention.

In the drawing:

Figure 1 is a longitudinal view partly in section, taken on the line 1—1 of Figure 4, and show-

ing the device being applied to the eye or ring bolt end of a line-clamp.

Figure 2 is a similar view taken on the line 2—2 of Figure 4, and showing the positions of the various parts for the eye-bolt to enter.

Figure 3 is a similar view, but showing the position of the various parts after the device has been given a quarter turn to prevent the removal of the eye of the bolt, and in position for rotating the eye-bolt to tighten the clamp, and showing a different means of attachment to the stick.

Figure 4 is an end view of the device in position for entering the eye-bolt.

Figure 5 is a cross sectional view taken on the line 5—5 of Figure 2, and showing the locking means for the socket.

Figure 6 is a cross sectional view taken on the line 6—6 of Figure 3, and showing the driving means between the socket and the head.

Referring to the drawing:

The device comprises an outer tubular head composed of a body member 10 and an integral pole socket member 11 having a common axis and the two aligned bores 12 and 13; the end of a pole or stick 14 is secured in the socket 13 in any suitable manner.

Rotatably mounted within the bore 12, is a socket-member 15 formed with a transverse slot 16 open at the upper end to receive the eye 17 of the bolt 18.

The upper end of the head member 10 is formed with a counterbore 19 within which is secured a cap 20 by the screws 21 threaded through the wall of the member and entering the periphery of the cap 20; said cap 20 being flattened as at 22 to fit within the flats 23 of the counterbore 19 and prevent any rotation between the cap 20 and the head member 10, retain said cap within the counterbore 19 and remove any strain from the screws 21; said cap is formed with an oblong tapered opening 24 for the passage of the eye 17.

The eye socket member 15 has three positions within the head member 10 and in relation to the cap 20; the neutral position as shown in Figures 1, 2, 4, and 5, where the slot 16 is in registry with the oblong opening 24 in the cap 20 to permit of the passage of the eye-bolt 17; the two driving or operating positions for either tightening or backing out the bolt 18 as shown in Figures 3 and 6, so that the stick can not drop off the eye.

Thus the socket member 15 has an oscillating movement of 180° within the body member 10 and is retained in any of these three positions by a catch, comprising a radial bore 25 formed

in one side of the socket member 15 at right angles to its axis and within which is mounted a ball 26 on the spring 27 adapted to enter any one of the three holes 28, 29, and 30 which are formed in the wall of the member 10 at an angle to each other.

For the purpose of driving the socket member 15 in either direction, the casing head member 10 is formed within the lower part of the bore 12 with an integral triangular lug 31, as shown in Figure 6, and located in the path of a similar lug 32 which is formed on the lower end of the socket-member 15, so that when the socket member 15 is in either of its driving positions (that is a quarter turn either way from neutral) the lugs 31 and 32 will contact with each other and the socket member 15 will be rotated by rotating the head 10.

As the slot 16 in the socket member 15 is at right angles to the oblong opening 24 in the cap 20, when in either of its driving positions, the eye 17 cannot be removed from the device, as the eye 17 will be at right angles to the opening 21 in the cap 20, and thus cannot be withdrawn there-through.

In using the tool, the eye 17 of the bolt 18 of a clamp is inserted through the opening 24 in the cap 20 and into the slot 16 of the socket member 15 and the same given a quarter turn within the head 10 to bring the slot 16 at right angles to the opening 24 and prevent the eye 17 from being removed.

The clamp is then placed on the feed wire by

use of the stick or pole 14, and the head 10 is rotated to tighten the bolt 18 after which, by a slight reverse movement, the socket 15 will be moved a quarter turn to bring the slot 16 and opening 24 into registry so that the tool may 5 be removed from the eye-bolt 17.

In Figure 3, I have shown the head 10 formed with a shank 33 having a slot 35 and a series of teeth 34 adapted to engage with registering teeth formed on a similar member having a socket 10 end secured to the stick, the two members being secured together in an adjustable manner by a bolt.

Having thus described my invention, what I claim as new and desire to secure by Letters 15 Patent, is:

In a stick-wrench of the class described, the combination of a head formed with an axial bore and mounted upon a stick, of a socket-member 20 formed with a transverse slot in its outer end and rotatably mounted within the bore of said head, a driving lug located in the bottom of said axial bore, a driven lug formed on the bottom of said socket-member in the path of said driving lug and adapted to contact therewith to rotate said 25 socket-member, and means for retaining said socket-member either in a driving, neutral or driven position within the head, comprising radial holes formed in the wall of said head and a spring actuated ball latch mounted in said 30 socket-member for selective engagement therewith.

STEPHEN P. BECKER.
